(57) **CLAIM**

The ornamental design for a palm tree license plate frame, as shown and described.

DESCRIPTION

FIG. 1 is a perspective front and right view of the palm tree license plate frame of the present invention, showing our new design.

FIG. 2 is a front elevational view of the license plate frame of the present invention.

FIG. 3 is a top plan view of the license plate frame of the present invention, the bottom plan view being the mirror image thereof.

FIG. 4 is a right side elevational view thereof, the left side elevational view being the mirror image thereof.

FIG. 5 is a perspective rear view thereof; and,

FIG. 6 is a rear elevational view thereof.

1 Claim, 2 Drawing Sheets
